UNITED STATES PATENT OFFICE.

TEDDY T. MURFAY, OF CHICAGO, ILLINOIS.

COLLAPSIBLE BOAT.

Application filed January 5, 1925. Serial No. 616.

This invention relates to boats, and especially to the smaller sizes of water-craft, such as row boats, canoes, and the like, of collapsible form, adapted for ready knocking down so as to be convenient for portability and storage in a small space. The main objects of the invention are to provide an improved form of collapsible boat; to provide such a device adapted for more compact assemblage of the parts when knocked down; to provide a boat of this sort adapted especially for packing on the running board of an ordinary automobile so as to constitute part of a camping outfit; to provide improved means for stiffening and supporting the boat frame when set up for use; to provide an improved form of construction for the water-tight covering; to provide an improved form of ribbing and fastening means therefor; to provide convenient and positively effective means for tensioning the frame and covering when set up; to provide an improved form of stem, stern-post, keel and gunwale construction; to provide an improved form and arrangement of propelling means; to provide such means adapted to be operated manually for both propelling and steering the boat; and to provide an improved form of buoyant stabilizing means of the nature of sponsons.

An illustrative embodiment of this invention is shown by the accompanying drawings, in which—

Fig. 1 is a plan of a boat set up and assembled ready for use, the detachable seats being omitted.

Fig. 2 is a vertical longitudinal section along the main axis of the boat, two seats being shown.

Fig. 3 is an enlarged cross section on the line 3—3 of Fig. 1.

Fig. 4 is a still further enlarged fragmentary section on the line 4—4 of Fig. 1.

Fig. 5 is a fragmentary detail of a flexible connecting member forming part of the gunwale portion of the covering and shows the adjacent ends of a pair of flexible steel ribs.

Fig. 6 is a fragmentary plan of the keel rod and adjacent flooring.

Fig. 7 is a fragmentary view of the keel tension member and shows also the adjacent ends of a group of ribs secured thereto (before attachment to the canvas covering).

Fig. 8 is a greatly enlarged sectional view showing in detail the front end struc-

ture which appears on a smaller scale at the left end of Fig. 2.

Fig. 9 is a corresponding view of the rear end construction appearing on a smaller scale at the right end of Fig. 2.

Fig. 10 is a fragmentary view in vertical axial section through the keel frame tensioning device, which is operated to expand the boat before the flooring is applied.

Fig. 11 is an enlarged plan of the front end of the boat.

Fig. 12 is an enlarged plan of the rear end of the boat.

Fig. 13 is a plan of the longitudinally folded water-tight wall or covering member, the ribs being shown by dotted lines, as also the edge of the bottom part.

Fig. 14 is a fragmentary view of the central floor member which extends lengthwise over the keel part, and serves as a keelson, as shown in Fig. 1.

Fig. 15 is an end view of the roll when the flexible covering is rolled up ready for storage.

Fig. 16 is an enlarged section on the line 16—16 of Fig. 13.

Fig. 17 is a section on the line 17—17 of Fig. 10.

Fig. 18 is a diagrammatic plan of the gunwale reinforcing strips for one side of the boat.

Fig. 19 is a greatly enlarged section on the line 19—19 of Fig. 2.

Fig. 20 is an enlarged underside view of one end of a seat showing the end fastening.

In the construction shown in the drawings, the boat comprises mainly three distinct essential parts, namely, a forcibly expandible rigid frame of jointed character, a substantially flexible wall or covering of water-tight character adapted to be stretched thereon, and a foldable floor. These main parts are supplemented by several minor fittings including gunwale strips, side-keelsons, seats and propelling means, as will be more fully explained.

The said frame part consists mainly of a telescopically jointed and extensible keel bar 1 having upright front stem and stern-post portions 2 and 3.

The flexible covering consists mainly of a thin wall member 4, preferably made of canvas suitably treated to render it water-tight, in combination with a double series of transverse flexible ribs 5 of resilient character, one series on each side, and flexible tension

members 6 and 7 connecting the gunwale tips of the ribs and the keel ends of the ribs respectively.

The flooring as a whole includes a full width bottom member 8 composed of a series of thin narrow boards 8' disposed crosswise and flexibly joined together at their edges and hinged together at their edges by hinges 8'', (see Fig. 9) a slightly elevated main center tread member 9 consisting of a series of wide boards 9' disposed end to end and hinged together and a pair of foldable side keelsons 10. The sections of the latter fold in opposite directions at successive joints as shown for the floor sections in Fig. 9. The floor bottom 8 is readily attachable to the main frame or keel 1 by means of U-bolts 11 when the latter is set up and in place, together with the side keelsons 10 which are laid before the flooring proper 8 is applied.

The method of assembling the boat for use is to first set up the extensible keel member 1, then apply the covering 4 over the frame thus provided, which is suitably expanded as will be explained, then set the side keelsons 10 in place and apply the flooring 8 and finally apply the tread part 9, the gunwale stiffening members 12, seats 13 and propelling means hereinafter described.

When the boat is to be knocked down and packed for transport or storage, the reverse operation is followed. The several detachable accessory parts, such as the propeller and seats, are first removed, the gunwale strips 12 are each taken off and folded up, the tread 9 and floor 8 are each folded, the side keelsons 10 are also removed and folded, the keel bar 1 is relaxed and separated from the covering 4 and taken apart and finally the part 4 is folded lengthwise and rolled into a compact bundle. The frame, floor and covering parts et cetera may be rolled into separate parcels, or if preferred the frame and other members may be rolled into or enfolded by the covering member 4, depending upon how it is desired to handle the boat when packed; a single large parcel being preferable under some circumstances and several smaller parcels being preferable under other circumstances.

Referring now to the structure of the frame more in detail, the keel 1 comprises five straight bar sections 14, 15, 16, 17 and 18, two of which, 15 and 17, are of relatively small diameter to fit as at 19 in the ends of the larger sections, which are of tubular form and adapted for limited overlap. The stem and stern-post 2 and 3 each include a horizontally turned lower end 2' and 3' respectively adapted for telescopic connection with the adjacent ends of the corresponding keel sections 14 and 18.

One of the keel joints as at 20 is provided with means, as shown in Fig. 10, for forcibly extending the keel 1 when it is in place, so

as to stretch the covering 4 thereon (see Figs. 10 and 17). This expanding means includes a rack bar 21 secured to the thin inner keel member 17 with the toothed end projecting so as to be engaged by a gear wheel 22 pivoted at 22' within and at the upper side of the next adjacent relatively large overlapping keel tube 16. Said gear wheel, which is adapted and arranged to serve also as a ratchet wheel, is provided with a downwardly forked detachable lever handle 23 for manual operation. A pair of gravity operated ratchets or pawls 24 and 25 are provided, one on said handle and one on bar 16, to insure operation and locking of the wheel when it has been thrown into its effective position respectively for tightly expanding the frame. Each ratchet is provided with a lift handle 26 and 27 respectively, whereby the ratchets may be disengaged when the wheel is to be released for collapsing the frame. The shank 21' of bar 21 is set in a filler block 28, which fits snugly in tube 17 and is secured by rivets 29. The tubes 16 and 17 are splined against relative turning, as shown at 30 on Fig. 17.

All of the other keel joints are formed and adapted for limited concentric overlap as shown by dotted lines on Fig. 2. The lap is limited by core blocks fixed in the larger tubes as will be understood.

When the keel one and covering 4 are properly assembled and expanded the side keelsons 10 are each unfolded and set in place. The floor 8 is then unfolded and fastened in place, centrally by the keel bolts 11 and laterally by the side keelson bolts 31. The tread strip 9 is next unfolded and secured by the bolts 32.

The four gunwale strips 12 are next unfolded and applied to the boat edges, one inside and the other outside, where they are secured by the downwardly facing U-clips 33 and screws or bolts 34, which extend through the adjacent rib tips, as shown in Fig. 19. These strips 12 are formed and arranged to break joints, as indicated in Fig. 18. For this purpose one of the end sections 12' of each strip is half as long as the rest of the sections 12''. One strip 12 of each pair has its short section 12' at the bow and the other strip has its short section at the stern.

The covering 4 is made integrally and is adapted to fold along the longitudinal center line corresponding with the keel, stem and stern lines, so that the two sides thereof come together in a substantially flat form adapted for rolling on their transverse axis to make a relatively short bundle having a length about the same as the middle ribs. In order to stiffen the covering and give the desired stability and form to the boat, the flat spring steel ribs 5 are attached thereto, one set on each side, the inner ends of the

ribs being flexibly joined, as will be described. In order to hold these ribs in place and to protect them, pockets or tunnels 35 are formed transversely on the inner side 5 of each lateral half of the covering by means of canvas strips sewed to the wall 4. The outer ends of the ribs are connected by loops 5' and rivets 36 and 37 to the chain 6 which is housed in a pocket 38 formed in the gun-
10 wale part of the covering. A keel pocket 39 is also provided for the middle chain 7. The inner ends of the ribs 5 are formed with loops 40 to engage the chain 7, these loops being riveted at 41. Straps 4' are 15 sewed to the inside of the cover 4 to receive the stem and stern posts 2 and 3.

In order to effectually stabilize the boat and render it non-sinkable, a pair of inflatable sponsons 42 are provided along the water line on the sides of the covering, for which purpose longitudinal pockets are sewed at 43 and 44 to the outside of the covering to receive tubular rubber air pockets 45, which are provided with upwardly projecting inflating stems 46 arranged for convenient access in order that air may be forced in when the boat is to be used.

A rigid connector cap 47 is provided at 30 the stem to receive and stably join the upper stem tip and gunwale members. A U-bolt 48 provided with butterfly nuts clamps this cap to the stem 2. A somewhat similar cap 49 is clamped by a U-bolt 50 to the upper tip 35 of the stern-post 3 and holds the adjacent ends of the gunwale strips 12.

The seats 13, as many as desired consistent with the size of the boat, are hung on lugs 51, one pair at each end, adapted to hook 40 over the gunwales and carry the seat a little below the upper edge. In order to prevent accidental displacement of the seat a spring catch 52 is provided at each end adapted to releasably engage the underside 45 of the inner strip 12, as shown by Fig. 20. The seats 13 serve also as thwarts or transoms and stiffen the boat.

In order to facilitate propelling the boat, a manually operated screw propeller 53 is 50 provided at the stern, which propeller by means of a flexible driving shaft 54 is connected to a gear box 55 bolted to the floor tread 9 and having an operating handle 56 in the form of a rock lever mounted thereon 55 in effective relation to the gearing, whereby suitable rotation may be imparted to the propeller. In order that the propeller 53 may serve also as a rudder, it is mounted at the lower end of an upright shaft 57 which 60 is journaled at its upper end in a journal block 49' formed as part of the stern cap 49, a horizontally disposed handle 58 being provided for swinging the propeller either to the right or to the left. The said flexible shaft 54 is enclosed in a flexible tubular

70 housing 59, which is connected to the front end of one arm 57' of the downwardly disposed T-head of the rudder post 57, on the other arm 57'' of which the propeller 53 is supported.

The propeller may be supplemented by oars whenever desired, oar-locks 60 being attachable to the gunwales as shown in Figs. 1 and 2.

75 Although but one specific embodiment of this invention is herein shown and described it is to be understood that numerous details of the construction shown may be altered or omitted without departing from the spirit of the invention as defined by the following 80 claims.

I claim:

1. A collapsible boat comprising, in combination, a flexible covering, an extensible stiffener whereon said covering may be 85 stretched, foldable gunwale members, said stiffener including a telescopically jointed keel bar having stem and stern-post members secured thereto, and manually operable means for forcibly extending said keel bar 90 when the said parts are set up and assembled for use as a boat.

2. In a boat of the character described a longitudinally extensible sectional keel including a pair of interfitting section rods 95 arranged and disposed for relative adjustment longitudinally, in combination with manually operable rack, ratchet wheel and dog means for forcibly extending said keel.

3. A knock-down boat comprising a flexible covering and a frame including a forcibly expansible jointed keel member, said keel member including a plurality of rigid sections and having upturned ends to serve as stem and stern-post respectively, and 105 mechanism to forcibly extend said keel member at one of its joints.

4. In a boat an extensible jointed keel member having a rack and a pinion secured to adjacent keel sections respectively at one of the joints, said pinion having a handle whereby it may be operated manually, and automatic pawl means to arrest said pinion when the keel has been forcibly expanded lengthwise.

5. A knock-down boat having a flexible covering and a frame which includes a sectional keel member, a pair of foldable side-keelsons disposed substantially in a horizontal plane with said keel member and a transversely jointed foldable floor member attachable along its main axis to said keel member and at its edges to said side keelsons.

6. A collapsible boat having a transversely foldable floor disposed entirely across the bottom in combination with an elevated tread member which is transversely foldable, and means for attaching same to the floor.

7. A collapsible boat having a frame part comprising a jointed keel rod with upturned

stem and stern-post members substantially rigid therewith, in combination with a water-tight covering having resilient ribs secured thereto, transversely foldable gunwale members detachably connected to the upper edges of the sides of the boat respectively, and end-cap members secured to the upper ends of the stem and stern-post respectively and adapted to receive the adjacent ends respectively of said gunwale members.

8. A collapsible boat having side keelsons of foldable character comprising a series of sections flexibly connected to fold in opposite directions at successive joints and means for securing the same detachably to the boat adjacent to the junction of the floor and side walls respectively.

9. A collapsible boat having transversely foldable gunwale strips detachably connected to the upper edges of the side walls of the boat respectively.

10. In a collapsible boat of the character described, gunwale stiffening means of foldable character demountably attached and comprising a pair of transversely jointed complementary rail-strips arranged to break joints relative to each other.

11. In a collapsible boat of the character described, gunwale stiffening means of foldable character demountably attached and comprising a pair of transversely jointed complementary rail-strips arranged to break joints relative to each other, in combination with fastening means including inverted U-clips to tightly embrace the rail strips in place on the boat edges.

12. A boat including a flexible wall in combination with a pair of transversely foldable gunwale stiffeners arranged to break joints and fasteners for said stiffeners including rigid means extending through said stiffeners and the said wall which is disposed between said stiffeners.

13. A boat including a flexible wall in combination with a pair of transversely fold-

able gunwale stiffeners arranged to break joints and fasteners for said stiffeners including screws extending through said stiffeners and the said wall which is disposed between said stiffeners.

14. A collapsible boat comprising mainly a knock-down frame in combination with a flexible water-tight covering therefor, said covering having flexible reinforcement means including resilient transverse ribs extending outwardly from the keel line, said ribs being joined in pairs at their inner ends for longitudinal folding of said covering.

15. A collapsible boat comprising mainly a knock-down frame in combination with a flexible water-tight covering therefor, said covering having flexible reinforcement means including a keel chain and gunwale chains and resilient transverse ribs extending outwardly from the keel line, said ribs being joined in pairs at their inner ends for longitudinal folding of said covering, said ribs being permanently connected at their ends to said chains respectively.

16. A collapsible boat of the character described comprising mainly a knock-down keel and a water-tight covering having transverse spring ribs, in combination with detachable transversely jointed gunwale strips, said keel having a stem and a stern-post each provided with a top cap to receive and hold the adjacent ends of said gunwale strips respectively.

17. In a collapsible boat of the character described, a jointed keel rod having a stern-post detachably connected thereto in combination with a top cap for said stern-post to receive the gunwale ends, and a screw propeller having a supporting post vertically journaled on said cap whereby said propeller may serve also as a rudder for steering the boat.

Signed at Chicago this 2nd day of January, 1925.

TEDDY T. MURFAY.
